VACUUM CUP DEVICE

Filed May 31, 1930

FIG. 2.

FIG. 1.

FIG. 3.

INVENTOR.
JOSEPH JANDA.

BY Reynolds

ATTORNEY.

UNITED STATES PATENT OFFICE

JOSEPH JANDA, OF RIDGEWOOD, NEW YORK

VACUUM-CUP DEVICE

Application filed May 31, 1930. Serial No. 457,708.

My invention relates to card or sign supporting devices of the vacuum-cup type, designed for temporary, detachable connection with any smooth surface, and my purpose, generally speaking, is to provide a device of this character which is of simple, inexpensive construction and which embodies means whereby information or advertising cards, signs or the like of paper, cardboard or other flexible material may readily be interchangeably mounted thereon and supported in a flat condition so that reading or display matter on the card, sign or the like may be clearly visible.

With the foregoing and other purposes in view, my invention consists in the novel features of construction, combination and arrangement of parts as will be hereinafter more fully described, illustrated in the accompanying drawings and defined in the appended claim.

In the drawings, wherein like characters of reference denote corresponding parts in related views:

Figure 1 is a central longitudinal section through a supporting device constructed in accordance with one embodiment of my invention.

Figure 2 is an end view of the device shown in Figure 1; and

Figure 3 is a view similar to Figure 1 illustrating a slightly alternative embodiment of the invention.

Referring to the drawings in detail, 10 Figure 1 designates a cup of elastic material, such as rubber, having a chamber 12 therein from which air is adapted to be expelled by collapsing the cup against any smooth surface, the margin of the cup surrounding the chamber being designed to adhere closely against the smooth surface so that atmospheric pressure exerted against the outer face of the cup serves to maintain same detachably supported against the surface.

Embedded in the central portion of the cup 10 is the inner end of a threaded pin or stud 14 which may project outwardly any suitable distance beyond the outer face of the cup. Preferably, the inner end of this pin or stud is provided with a polyg-

onally shaped head 16, whereby the pin or stud is held securely both against being pulled out of the cup 10 and against rotation relative to said cup.

Adapted for detachable connection with 55 the cup 10 through the instrumentality of the pin or stud 14, is a card or sign supporting plate or disk 18 which is formed from some stiff, preferably light weight material, such, for example, as aluminum. This plate 60 or disk, which may be of any suitable size and shape, is flat and, in the case of Figures 1 and 2, is provided with a central aperture whereby it is freely engageable over the pin or stud 14 into abutting relation at its center with the outer face of the cup 10. In this connection it will be observed that the outer face of the cup 10 is inclusive of a flat surface 20 surrounding the pin or stud 14, against which surface the plate or disk is 70 adapted to abut, whereby tilting movement of the plate or disk relative to the cup is prevented.

The plate or disk 18 is designed to support on its outer face a card, sign or the like 75 22, formed from paper, cardboard or other flexible material, and which, like said plate or disk, is provided with an aperture to receive the pin or stud 14, the plate or disk 18 with the card or sign 22 superimposed 80 thereon being adapted to be secured to the cup in the example of Figures 1 and 2 by means of a clamp nut 24 threaded on the pin or stud 14.

On the other hand, according to the embodiment of the invention illustrated in Figure 3, the necessity for a nut 24 may be eliminated by providing the plate or disk, designated in this figure as 18^a, with a threaded aperture to adapt said plate or disk for direct threaded engagement with the pin or stud 14, in which event the plate or disk, preferably but not necessarily, is provided with a boss or enlargement 26, for strengthening purposes where the threaded aperture 95 is formed therein.

When a nut is employed, as in Figures 1 and 2, to secure the plate or disk and the card or sign to the cup 10, the said nut may be employed to secure the central portion or 100

the card or sign against the plate or disk and other means may or may not be provided to hold the marginal portions of the card or sign against the plate or disk. However, in the case of Figure 3, wherein the clamp nut is eliminated, it is particularly desirable to provide means for holding the marginal portions of the card or sign against the plate or disk, and in order to 10 accomplish this purpose in a simple, effective manner, the marginal portion of the plate or disk 18^a may be turned outwardly and then inwardly to provide a lip 28 disposed in overlying relation to the outer, marginal portion of the plate, thus to produce a groove to receive and retain the marginal portion of the card or sign, which latter may be flexed into engagement with said groove in an obvious manner. Thus, even 15 20 though the central portion of the card or sign may be provided with an opening of relatively large size to receive the boss 26, and despite the absence of a clamp nut at the center of the device, the card or sign obviously will be retained and supported in a substantially flat condition by the plate or disk.

Preferably the plate or disk 18 of Figures 1 and 2 also is provided with a marginal 30 lip and groove for the same purpose as set forth in respect to the lip and groove shown in Figure 3, but as heretofore stated this is not essential, especially as it is evident that with the construction illustrated in Figures 35 1 and 2, the size and shape of the card or sign may differ materially from the size and shape of the plate or disk and still be held flat against the plate or disk by the nut 24.

From the foregoing description considered 40 in connection with the accompanying drawings, it is believed that the construction and the advantages of my improved support will be clearly understood. I desire to point out, however, that while I have herein illustrated 45 and described certain specific embodiments of my invention, modifications and changes may be made therein within the spirit and scope of my invention as defined in the appended claim.

50 I claim:

A supporting device of the character described comprising a vacuum cup, a pin embedded at one end in said cup, said pin having a threaded portion projecting forwardly 55 from the cup and the cup having a flat front face surrounding said pin, a flat stiff card or sign supporting plate having an aperture therein, said plate being disposed flat against the flat front face of the vacuum cup with said pin extending through the aperture in said plate, a forwardly and inwardly directed marginal flange on said plate cooperating with the latter to provide 60 a retaining groove for the marginal portion 65 of a card or sign, a card or sign disposed

flat against the front face of said plate with its marginal portion disposed in said groove, said card or sign having an aperture receiving said pin, and a nut threaded on said pin against said card or sign and clamping the latter against said plate and the plate against 70 the flat face of the vacuum cup.

In testimony whereof I affix my signature.

JOSEPH JANDA.
